TRANSPORTATION VEHICLE

Walter H. Gollwitzer, Birmingham, Mich., and William B. Shenk, Jr., Rodenkirchen Cologne, Germany, assignors to Ford Motor Company, Dearborn, Mich.

Filed Jan. 7, 1972, Ser. No. 216,328

Term of patent 14 years

Int. Cl. D12—08

U.S. Cl. D14—3

FIG. 1

FIG. 1 is a perspective view of a transportation vehicle according to our new design;

FIG. 2 is a side elevation view of the transportation vehicle taken in the direction of arrow 2 of FIG. 5;

FIG. 3 is an end elevational view of the transportation vehicle taken in the direction of arrow 3 of FIG. 5;

FIG. 4 is an end elevational view of the transportation vehicle taken in the direction of arrow 4 of FIG. 5;

FIG. 5 is a plan view of the transportation vehicle; and

FIG. 6 is a side elevational view of the transportation vehicle taken in the direction of arrow 6 of FIG. 5.

We claim:

The ornamental design for a transportation vehicle, substantially as shown.
